UNITED STATES PATENT OFFICE.

JOHN E. MUHLYFELD, OF SCARSDALE, AND HERMAN F. BALL, OF NEW YORK, N. Y.

CAR-TRUCK.

1,190,791.

Specification of Letters Patent. Patented July 11, 1916.

Application filed April 28, 1915. Serial No. 24,497.

To all whom it may concern:

Be it known that we, JOHN E. MUHLYFELD, of Scarsdale, in the county of Westchester and State of New York, and HERMAN F. BALL, of the borough of Manhattan, in the city, county, and State of New York, have jointly invented a certain new and useful Improvement in Car-Trucks, of which improvement the following is a specification.

10 The object of our invention is to provide a truck for railroad vehicles, the side frame members of which shall be so constructed and connected that they will be held rigidly against relative lateral motion; the squareness of the truck in a horizontal plane will be assured, while flexibility in relation to irregular track conditions, and a limited degree of frame torsional movement is permitted; that the weight of the vehicle will 20 be carried on the side members as upon beams which are practically uniformly, instead of centrally loaded, thereby materially reducing the maximum bending moment and enabling a corresponding reduction of 25 weight to be made; and that disconnection of the side members in the event of derailment or other accident shall be prevented.

The improvement claimed is hereinafter fully set forth.

30 In the accompanying drawings: Figure 1 is a view, the right hand half of which is a vertical longitudinal section, taken partly through the middle transverse plane of a journal box, and partly through the middle 35 transverse plane of the entire structure, and the left hand half, a side view, in elevation, of a car truck, illustrating an application of our invention; Fig. 2, a view, the right hand half of which is a horizontal section, taken 40 through the axial lines of an axle and of a journal box and pivot, and the left hand half, a plan view; Fig. 3, a view, the right hand half of which is a vertical transverse section, taken on the line $x-x$ of Fig. 1, 45 and the left hand half, a similar section, taken in the middle transverse plane of the truck; and, Fig. 4, a similar section, illustrating a structural modification.

Our invention is herein illustrated as applied in a four wheeled car truck, the frame of which is composed of two side members, 1, which, in this instance, are shown as integral castings, of hollow or tubular section, each having a horizontal spring bearing, 1^b, formed on its top, at each of its

ends, and a transom, 2, which extends from one to the other of the side members in and adjoining the middle transverse plane of the truck. The ends of the transom are, as shown in Figs. 1 and 2, made of greater width than that of the remainder of its length, and it is supported, without any positive connections, on pairs of horizontal bearing faces, 1^c, formed on the tops of the side members, the members of each pair of bearing faces being spaced at a proper distance apart to receive abutting faces on the bottom of the transom. Under this construction, the load imposed upon the rigid transom is transmitted therefrom to each of 70 the side members of the frame, at two points, which are located at as great a longitudinal distance apart as practicable, the load being thereby distributed on the length of the side members, instead of being applied at and 75 near the central transverse planes thereof, and a limited degree of flexibility between the transom and side members is permitted.

As shown in Figs. 1 to 3 inclusive, the transom is held against lateral movement 80 relatively to the side frame members, 1, 1^a, by downwardly projecting tenons, 2^a, which fit in corresponding recesses or sockets in the tops of the side frame members, and by downwardly projecting lips, 2^b, formed centrally on its ends and extending over the adjoining portions of the side frame members. Fig. 4 shows the transom as provided with lips, 2^b, which engage the side frame members, on opposite sides of the bearing 90 faces, 1^c, and perform the same function as the tenon and socket construction above described. Any substantial degree of relative movement of the transom and side frame members, more particularly vertical detachment of the former from the latter, is positively prevented by pins, 2^c, passing through lugs, 2^d, on the bottom of the transom, and lugs, 1^e, on the side frame members, and held in position by keys or cotters, 2^e. 100

It will be seen that by the above construction, the connection of the transom to the side frames is effected in a simple and thoroughly substantial manner, and at points which are at the maximum distance apart longitudinally upon the side members. The advantage of the latter feature, in promoting uniform distribution of load to the side members, and maintaining the normal squareness of the truck frame, as well as in 110

permitting flexibility of the frame in running over irregular track, will be apparent to those who are familiar with the operation of railroad rolling stock.

- 5 The truck wheels, 3, are secured, in the usual manner, on axles, 3^a, the journals, 3^b, of which rotate under bearings, 4^a, fitted in journal boxes, 4, each of which is adapted to move vertically, but not laterally or longitudinally, relatively to the frame, by the following means: Each of the journal boxes, 4, is formed integral with, or rigidly connected to, an arm, 4^c, which is pivotally connected to the side frame supported by the 10 journal box, by a pin, 4^d, passing through the inner end of the arm and through a long bearing or bearings on the side frame member. As shown in Fig. 1, the arms, 4, are forked, their upper and lower members fitting 15 against the top and bottom of the journal box, respectively, and they are secured thereto by vertical bolts or rivets, 4^e, located on opposite sides of the journal box. The degree of relative movement of the side 20 frame members and the journal box arms and journal boxes, is limited by links, 4^f, fitted in perforations in the ends of the upper members of the journal box arms.

The truck frame is supported on the journal boxes through the intermediation of springs, 5; a nest or plurality of which is interposed between each of the spring bearings, 1^b, of the side members, and an equalizing plate, 6, which bears centrally on the 30 upper member of the adjacent journal box arm, 4^c, and provides, on its upper surface, a lower bearing for the springs, 5.

We claim as our invention and desire to secure by Letters Patent:

- 40 1. In a railroad truck, a frame comprising two side members, a transverse connecting member which is supported, without positive connection, on each of the side members upon bearing faces thereon located at substantial distances from the central transverse plane of the truck, and means for de-

tachably, but not rigidly, connecting the transverse member to the side members.

2. In a railroad truck, the combination of two side frame members, each having two bearing faces located at substantial distances from its middle transverse plane; a transom having end faces supported, without positive connection, on said bearing faces and lugs depending from its bottom in its middle longitudinal plane, and means for detachably, but not rigidly, connecting said lugs to the side members.

3. In a railroad truck, the combination of two side frame members, each having two bearing faces located at substantial distances from its middle transverse plane; a transom having end faces supported, without positive connection, on said bearing faces, means for connecting lateral engagement of the transom with the side frame members, with the capacity of flexibility without substantial relative lateral movement, and means for detachably, but not rigidly, connecting the transom to the side frame members.

4. In a railroad truck, the combination of two side frame members, each having two bearing faces located at substantial distances from its middle transverse plane; a transom having end faces supported on said bearing faces; interlocking projections on the transom, laterally engaging the side members, adjacent to said bearing faces; downwardly projecting lips on the transom, adjoining the outer faces of the side members, in the central transverse plane of the truck; lugs depending from the bottom of the transom, in said plane; and pins passing through said lugs and through projections on the inner faces of the side members and detachably connecting the transom and side members.

JOHN E. MUHLFELD.
HERMAN F. BALL.
